The ornamental design for a carburetor, as shown and described.

DESCRIPTION

FIG. 1 is a top front perspective view of a carburetor showing our new design.

FIG. 2 is a bottom rear perspective view of the carburetor illustrated in FIG. 1

FIG. 3 is a top plan view of the carburetor illustrated in FIG. 1.

FIG. 4 is a bottom plan view of the carburetor illustrated in FIG. 1.

FIG. 5 is a side elevation view of the carburetor illustrated in FIG. 1.

FIG. 6 is another side elevation view of the carburetor illustrated in FIG. 1.

FIG. 7 is a front elevation view of the carburetor illustrated in FIG. 1; and,

FIG. 8 is a rear elevation view of the carburetor illustrated in FIG. 1.
